TOOL FOR ROTATING SCREWS AND
OTHER OBJECTSNicholas William John Walsh, Doncaster,
Victoria, AustraliaApplication December 8, 1934, Serial No. 756,643
In Australia November 22, 1932

6 Claims. (Cl. 145—50)

This invention relates to tools of the type in which the force of a blow is utilized to cause pressure, shock and turning movement to be transmitted simultaneously for the purpose of turning screws and other objects. Tools of this type are particularly useful for loosening corroded screws and bolts and for tightening screws in electrical machinery.

The object of this invention is to provide a compact and efficient tool of the type referred to, which does not require special skill to use and which is arranged to transmit turning movement in either direction at will, such direction being determined by preliminary rotation of a hand-piece.

This improved tool includes a tubular hand-piece and within said handpiece two members on which are co-operating helical faces, one of said members being rotatable relatively to the hand-piece and the other non-rotatable, the said members being normally located by spring means so that a primary rotary movement of the hand-piece enables the direction of rotation of the rotatable member to be determined.

But in order that this invention may be more readily understood it will now be described with reference to the accompanying drawing in which:

Fig. 1 is a sectional elevation of a tool fitted with an adaptor and a screw-driver bit.

Fig. 2 is a diagrammatic view showing the position of the parts for transmitting rotary movement in a counter-clockwise direction.

Fig. 3 is a fragmentary view of parts in Fig. 2 after operation.

Fig. 4 is a diagrammatic view showing the position of the parts for transmitting rotary movement in a clockwise direction.

Fig. 5 is a fragmentary view of parts in Fig. 4 after operation.

1 is a tubular handpiece having a solid head 7^a and a flanged end 7^b. Members 8 and 9 are arranged within the handpiece and each said member has any suitable number of approximately V-shaped recesses 10, 11. Member 8 is rotatable

45 relatively to the handpiece while member 9 is fixed against rotation relatively thereto and may be integral with head 7^a which is connected to the casing 7 by a screw thread 7^c and in addition is suitably fixed thereto as by welding.

50 Each face 10^a, 11^a respectively of recesses 10 and 11 is helically curved so that when a face 10^a is in contact with a face 11^a and member 9 is moved toward member 8 the latter is partially rotated. Member 8 is normally located against

55 an abutment such as a casing flange 7^b by means

of a spring 12 which is arranged in recesses 12^a in the members 8 and 9. When the members 8 and 9 are spaced apart the maximum distance longitudinally the parts 10^b between recesses 10, and the parts 11^b between recesses 11 overlap.

The end 8^a of member 8 projects beyond the end 7^b of casing 7 and is adapted to carry a suitable fitting as a socket 13 to hold a tool such as a screw-driver bit 14, which may be provided with a groove 14^a to be engaged by a spring pressed stud 13^a.

The size and shape of head 7^a are variable and it may be provided with a transverse hole 15 to receive a tommy-bar to assist turning when the tool is used for ordinary twisting purposes.

In use, end 8^a of the rotatable member 8 is fitted with suitable means to engage the object to be turned, for example if the object is a screw having a slotted head a socket as 13 and a screw-driver bit as 14 is fitted and the end of the bit is fitted in the screw slot. The handpiece 7 is then rotated in the direction in which the screw is to be turned until the complementary faces 10^a, 11^a are in contact. If a right-hand threaded screw is to be tightened the handpiece is turned anti-clockwise to the position illustrated in Fig. 4 while if such a screw is to be loosened the handpiece is turned clockwise until the parts are positioned as in Fig. 2. The head 7^a is then struck with suitable implement such as a mallet, causing the handpiece 7 and member 9 to move rapidly and transmitting pressure, shock and turning movement simultaneously to member 8. Release of handpiece 7 allows the spring 12 to move the members 8 and 9 to normal position after which further partial rotation of the handpiece again locates the parts 8 and 9 in operative position. A few blows is sufficient to loosen even firmly fixed and corroded screws without damage. If a broken or smooth-headed screw or stud is to be rotated, a bit having a cold-chisel point of suitable form may be employed. If a nut or bolt head is to be engaged, a tube spanner socket or other suitable fitting may be fitted to end 8^a.

I claim:

1. A tool for turning screws and the like, comprising a handpiece, a rotatable member and a non-rotatable member in said handpiece, means to locate said members in spaced apart positions, and co-operating helical faces on said members whereby when a blow is transmitted to the non-rotatable member, the rotatable member is caused to transmit pressure, shock and rotary movement to a tool connected to it.

2. A tool for turning screws and the like com-

prising a tubular handpiece and within said handpiece a member fixed thereto and another member which is relatively rotatable and movable longitudinally, V-shaped recesses with helical faces on both said members, means to locate said members in spaced apart but inter-engaging position, so that when said handpiece and the non-rotatable member are rotated relatively to the rotatable member co-acting helical faces engage whereby pressure, shock and rotary movement may be transmitted to the rotatable member, the direction of rotation of the said member being determined by the direction of rotation of the handpiece.

10 3. A tool as in claim 1 within each said member a plurality of approximately V-shaped recesses with co-operating helical faces, the projections between the recesses overlapping when said members are in spaced apart position.

4. A tool for turning screws and other rotatable elements comprising a tubular handpiece having a head at one end and a flange at the other end, a member within the handpiece and fixed to said head, a partially rotatable member within the handpiece which is longitudinally slidable between said flange and the fixed member, spring means to normally locate said slidable member, a pair of V-shaped recesses with helical faces in each said member and projections between said recesses which overlap.

5. A tool as in claim 4 within the head a transverse hole to receive a bar.

6. A tool as in claim 4 in which the fixed member is integral with the head, and means to connect said head to the casing.

NICHOLAS WILLIAM JOHN WALSH.
